APPARATUS FOR GRINDING BUSHINGS ON
CENTERLESS GRINDERS

Edgar W. Buebel, Baltimore, Md., assignor to
The Glenn L. Martin Company, Middle River,
Md., a corporation of Maryland

Application July 18, 1945, Serial No. 605,763

4 Claims. (Cl. 51—103)

1

My invention relates to apparatus for centering cylinders in a centerless grinder and more particularly a device that provides for grinding the external periphery of a bushing concentric to its bore when used in conjunction with a centerless grinder.

The use of centerless grinders to grind the outside surfaces of cylindrical parts to tolerances of micro-inches is well known. In accordance with prior art practices the part is not held, but laid on a work rest blade between a regulating or feeding wheel. The regulating wheel is set at an angle with respect to the axis of the grinding wheel so that as the regulating wheel rotates there will be a component of force created lengthwise of the work support blade tending to urge the part being ground across the grinding surface of the grinding wheel. This method has many advantages, but as it is necessary for the part to be laid in position for grinding without regard to the center of its bore it is impossible to grind apertured work pieces, like bushings, that must be ground to close limits of concentricity. A former method of working such pieces requires that the work piece be press fit mounted on an arbor held between fixed centers. The grinding wheel is then run back and forth in contact with the worked surface until the piece is ground to the desired size. This method permits the circular exterior of the work piece to be ground to close tolerances relative to the centerline of the aperture, however, as each piece requires a machine "setting-up" operation it is costly and slow. Work pieces worked in accordance with this method also are susceptible to considerable scoring of the bore by particles of abrasive material deposited on the arbor surface.

The present invention provides an adjustable bracket having a pivoted arm adapted to position an arbor carrying a cylindrical work piece to be ground so that the piece is fed to the grinding wheel of a conventional centerless grinder and held on a given axial centerline until the external periphery thereof is ground concentric to the given centerline and position said piece for further movement across the face of the grinding wheel, whereby the concentricity of the center of a drilled hole in a work piece is held to micro-inch tolerances relative to the center of the periphery of the work piece. Its design provides for changeability of arbors over a wide range of sizes. The shortness of the arbor relative to the travel of the work piece and the pivoting arrangement of the arbor holding blade is such as to greatly reduce exposure of the interior sur-

2

face of the bushing to score producing particles of abrasive.

It is among the objects of my invention to provide a means for centering cylinders for grinding in a centerless grinder wherein an adjustable bracket supporting a pivotally mounted blade is arranged to position a centered arbor carrying a cylindrical centered work piece through an initial stage of grinding in a centerless grinder.

10 Another object of this invention is to provide a means according to the preceding object of automatically grinding the external surface of a bushing concentric to the center of the periphery of the aperture in the bushing.

15 Other objects of this invention will become apparent from the following description in which reference is made to the accompanying drawing wherein like numbers refer to like parts in the different views.

20 In the drawing:

Figure 1 is a perspective view of the device of my invention in operating position feeding a bushing to the grinding wheel and showing two previously "feed" bushings in advanced stages of being ground.

25 Figure 2 is a perspective view of the device in open position showing the blade carrying the arbor in vertical position.

Figure 3 is a fragmentary vertical sectional view of a grinder showing the relative position of the arbor to the regulating and grinding wheels.

30 Referring in detail to the drawings I have illustrated the preferred embodiment of my invention as an improved feeding device for feeding cylindrical work pieces to a conventional centerless grinder. This type of grinder is known in the art as an in-feed grinder having a regulating wheel 10 disposed at a slight angle to the axis of a grinding wheel 11 so that as the feed wheel 40 rotates it creates a slight urge upon the work piece tending to receive and draw it across the face of the grinding wheel. The work piece is supported by a work rest 12 positioned parallel to the face of the grinding wheel 11 across which it 45 moves as the grinding operation is performed. The spacing of grinding wheel 11 from the feed wheel 10 determines the amount of cut.

45 The device 13 of my invention is mounted on the side wall 14, or support of a centerless grinder 50 as illustrated in Figure 1. A supporting bracket 15 having a slotted vertical portion 16 and a tongued platform 17 is adjustably mounted on wall 14 and secured thereto by stud bolts 18 inserted through vertical slots 19. Vertical adjustment of the support is accomplished by loosening

bolts 18 and moving the bracket 15 vertically as required for positioning various sized work pieces.

Slidably mounted on the platform 17 of bracket 15 is a block member 20 formed with a base 21 and two upright side members 22 arranged to form a channel 33. Base 21 of the block 20 is formed with a groove 23 arranged to receive tongue 24 of the platform 17 forming a longitudinal dovetail joint between the block 20 and platform 17 which restricts the block 20 to longitudinal movement relative to the platform 17. Base 21 is provided with an extension 25 which extends outward and downwardly from base 21 to form an angled adjusting bar apertured to receive an adjusting means. Extending outwardly from platform 17 is a threaded rod 26 aligned with the aperture in the angled end 29 of extension 25 to provide an adjusting means by which block 20 may be horizontally positioned relative to platform 17 and secured in place by means of an outer nut 27 and an inner nut 28 positioned to secure angled portion 29 of the extension 25. This longitudinal adjusting means, providing horizontal movement of block 20 along an axis parallel to the grinding wheel 11, provides my device with a wide range of adjustment for working pieces of various lengths.

A bar or blade 31 is pivotally mounted in channel 33 of the block 20 so that the end portion 32 thereof can be raised away from the grinding wheel 11 to an upright, or vertical, position as shown in Figure 2. Blade 31 is formed with a socket 33 in the end portion 32 to receive arbor 34 held in position by locking screws 37 or a like holding means. The opposite end of blade 31 is drilled to receive a rotative pivot pin 38, or a like pivoting means, positioned in holes, or sockets, formed in the side members 22 of block 20. I have found it desirable to arrange the point of pivot of the aforescribed pivoting means beyond the center of block 20 away from the grinder a sufficient distance so that the natural tendency of the blade is to drop to a horizontal or engaged position when moved forward from a vertical position. With this arrangement I utilize the unbalanced weight of blade 31, which is preferably made from heavy wear resistant bar stock, and the snugness of fit between blade 31 in channel 33 to secure a firm holding means for the work piece 39 during the grinding operation. Blade 31 is provided with a handle 36 positioned adjacent the pivot by which the blade 31 can be readily moved to the vertical position shown in Figure 2.

The arbor 34 is proportioned to be inserted in socket 33 of the blade 31 and is formed with a shoulder 38. The receiving portion of arbor 34 is formed to any desired diameter determined by the diameter of the aperture in the bushing to be worked and of sufficient length to support the work piece 39 concentric to the axial centerline of the arbor 34 as the work piece moves across the work face of grinding wheel 11 for a distance equal to the length of the work piece 39 as shown in Figure 1. The length of arbor 34 is varied in accordance with the length of work piece 39 to be ground. The length of the receiving portion of arbor 34 should be approximately one and one half times the length of the work piece in order to hold it in alignment during the first stage of the grinding operation in which it is ground over its entire length, thereby removing any eccentricity of its external surface relative to the bore.

The operation of my device may be briefly

stated as follows: An arbor 34 of the size required for the piece to be worked is inserted in socket 33 of blade 31 and secured by tightening screws 37. A work piece 39 is slidably positioned on the receiving portion of the arbor 34 as illustrated in Figure 2. The blade 31 is pivotally moved to grinding position and platform 17 vertically adjusted so that work piece 39 will rest upon work rest 12. The block 20 is longitudinally adjusted to place shoulder 38 of the arbor 34 adjacent work rest 12 so that work piece 39 in its initial position will have a feed-in contact of approximately $\frac{1}{2}$ of an inch with the grinding wheel 11. This set-up positioning is illustrated in Figures 1 and 3. The arbor 34 is raised and held in vertical position until the grinding wheel 11 and feed wheel 10 are brought up to full operating speeds by means of an electric motor, not shown, or some other like driving means.

The arbor 34 is then pivoted to grinding position shown in Figure 3 with work piece 39 being moved into engagement with the regulating wheel 10 and grinding wheel 11. As the regulating wheel 10 draws the work piece 39 across the face of the grinding wheel 11 the external periphery of the work piece is ground truly concentric to the hole in the work piece which is held to the axial centerline of arbor 34. After having traveled the length of the work portion of the arbor 34, which is approximately one and one half times the length of the work piece, the work piece 39 in its true concentric form moves clear of the arbor and along the work rest 12 to be completely ground in the conventional manner (See Figure 1).

Although I have described both vertical and horizontal adjustments in detail it will be understood that either adjustment can be varied independent of the other, such adjustment, or adjustments, being governed by the length and diameter of the piece to be ground. Also, it will be understood that once a setting is established no further adjustment will be required for a given size piece irrespective of the number of pieces ground.

Although the preferred embodiment of my invention has been shown as a feeding device as shown and described in detail and its environment referred to as working bushings, it will be appreciated that certain changes, alterations, modifications, and substitutions can be made without departing from the spirit and scope of the appended claims.

I claim as my invention:

1. A centering device for a centerless grinding machine having a work rest positioned between a regulating wheel and a grinding wheel mounted upon a base, comprising an adjustable supporting bracket mounted on said base, a block formed with a base portion and a channel portion adjustably mounted on the supporting bracket, a blade pivotally mounted in the channel of said block and having a socket formed in one end, an arbor formed with a receiving portion at one end adapted to receive and hold an apertured work piece and an inserting portion at the opposite end which provides for mounting in said pivoted blade, and a handle mounted in said blade at the point of fulcrum providing manual means for pivotally moving the blade to a longitudinal position relative to the work rest with the arbor mounted in the end of said blade positioned longitudinally adjacent the work rest and transversely adjacent the grinding wheel.

2. A positioning device for a grinding machine having a work rest, a grinding wheel and a regu-

lating wheel positioned to receive and grind a cylindrical work piece, comprising a supported base having a channeled portion, a blade movably mounted in said channel with an end formed with a socket and positioned adjacent the grinding wheel, an arbor adapted to be inserted in said socket and having a receiving end adapted to receive a cylindrical work piece, and adjusting means by which said work piece is moved into grinding contact with the grinding wheel.

3. A positioning device for a grinding machine having a work rest, a grinding wheel and a regulating wheel mounted on a base, comprising a supporting bracket mounted on said base, a channeled block adjustably mounted on said bracket, a blade adjustably mounted in said channel transversely to the grinding wheel, an arbor carried by said blade and formed with a work receiving portion, said work piece receiving portion being positioned and arranged to support a work piece for rotational and axial movement in contact with said grinding wheel and supported by the work rest.

4. A centerless grinding machine having a work rest, a grinding wheel and a regulating wheel mounted on a base having a side wall and arranged to grind cylindrical work pieces, comprising a bracket mounted on said side wall with adjustable attaching means and formed with a tongued platform portion, a

block formed with a base and side members forming a longitudinal channeled section above the base which is grooved to form a tongue and groove joint with said platform providing a longitudinal slide fit therewith, an extension extending from said base and arranged to provide longitudinal adjusting means between the block and platform, a pivoted blade having a socket formed in one end and adapted to be mounted in said channel, an arbor formed with a work receiving portion of approximately one and one half times the length of the work piece to be ground and having a securing portion adapted for insertion in said socket, an actuating handle for pivotally moving said blade carrying a work piece to a grinding position on the work rest in contact with the grinding and regulating wheels.
